UNITED STATES PATENT OFFICE.

JOHN O. STANLEY, OF HOLYOKE, MASSACHUSETTS.

SAFETY CRANKING DEVICE FOR EXPLOSIVE-ENGINES.

1,073,058.

Specification of Letters Patent.

Patented Sept. 9, 1913.

Application filed September 28, 1912. Serial No. 722,869.

To all whom it may concern:

Be it known that I, JOHN O. STANLEY, a citizen of the United States of America, and resident of Holyoke, in the county of Hampden and State of Massachusetts, have invented certain new and useful Improvements in Safety Cranking Devices for Explosive-Engines, of which the following is a full, clear, and exact description.

10 This invention relates to safety "cranking up" or starting devices for explosive gas engines, that is to devices operative in the manner of an ordinary simple crank for forwardly turning the engine starting shaft, 15 but which are susceptible, under a back fire when the engine shaft and starting shaft are violently reversely moved, of having the crank or manually operating member thrown out of clutch with and free from the starting shaft whereby no injury may come to the person attempting to crank up the engine.

The objects of the invention are to construct safety cranking devices of a comparatively few parts, all of which are of simple construction and practicable of manufacture at low cost, and, furthermore, to provide a device which is durable, reliable and efficient in operation and not subject to derangement 30 after protracted use.

The invention is described in conjunction with the accompanying drawings and is set forth in the claims.

In the drawings:—Figure 1 is substantially a side elevation of the safety cranking device combined with the starting shaft, which latter is in usual juxtaposition to the engine shaft with which it is adapted to be clutched and unclutched. Fig. 2 is a central longitudinal sectional view, on a larger scale, through the improved safety cranking mechanism. Fig. 3 is a cross sectional view on line 3—3, it being especially noted that this view is seen as looking from the rearward, as indicated by the arrow shown in connection with the section line. Fig. 4 is a cross sectional view, as taken on the line 4—4, looking to the rearward. Fig. 5 is a cross sectional elevation as taken beyond the plane indicated on the line 5—5, looking forwardly. Fig. 6 is a partial cross sectional elevation showing relative size and relation of parts to be hereinafter especially referred to. Fig. 7 is a perspective view showing the component elements of the device in separated relations.

Similar characters of reference indicate corresponding parts in all of the views.

In the drawings, A indicates a portion of the engine shaft having a clutch member *a* thereon; and B represents the starting or cranking shaft provided with a clutch member *b* for coaction with the one *a* when the starting shaft on which the crank C is mounted is forced rearwardly through the stationary support and guide *e* against the spring *f* as usual.

The starting shaft B has a cylindrical flange-like portion D at its outer end,—the same to all intents and purposes being as an integral part of the shaft although for practicability of construction it is produced as a collar or sleeve which is fitted on the end and keyed to the shaft. This cylindrical flange-forming portion D is provided with a series of regularly spaced grooves *g* longitudinally extending from the inner end of such part for a suitable distance as shown.

E represents a sleeve loose on the shaft 80 slightly separated from said groove-provided shaft portion D, and having a series of peripheral grooves *h* corresponding in number and spacing to, and adapted to align with, the grooves *g* of the said shaft flange 85 portion D.

G represents an apertured disk or flat ring, herein termed a "tumbler" arranged facewise against the end of the sleeve E, between the latter and the shaft flange D, this 90 element loosely encircling the shaft.

The tumbler ring is of very slightly larger diameter than the diameters of the sleeve E and shaft flange, which two parts are of equal diameter; and the tumbler ring has, 95 edgewise provided, a series of grooves or notches *i* in number and spacing corresponding to those of the sleeve E and shaft flange D,—the bottoms of all of the notches *g*, *h*, and *i* being coincident with an imaginary 100 circumference.

The tubular hub *j* of the crank C has an encircling relation about portions of the lengths of the shaft flange D and sleeve E, and the interposed tumbler disk G in which the grooves or notches are provided; and the crank hub has a plurality of pawls *k* in tangential sockets therein inwardly pressed by the springs *m*, which latter are in abutment against the screw plugs *n*; and through the means of these pawls, when the crank is rotated forwardly or clockwise for starting 105 110

the engine, the starting shaft will be rotated in the forward direction, the pawl engagement between the crank and starting shaft flange rendering, for forward driving the crank in effect the same as if it were rigidly fastened to the shaft; and the forward driving of the crank forwardly rotates the sleeve E and disk G.

It is to be perceived that the tumbler disk 10 has a pair of opposite arc shaped slots *o o* through which short pins or studs *p* projecting from the end of the sleeve E engage and the spring *r* sunk within a pocket *q* therefor in the end of the sleeve and having, 15 by its one end, an engagement with the sleeve and by its other end an engagement with the tumbler disk, its torsional reaction being such, when permitted so to do, to throw the tumbler disk around on the end 20 face of the sleeve E so that its notches *i* will be out of registry with the grooves *h* in the sleeve, the pin and slot provisions before referred to so limiting the rotative movement 25 of the tumbler disk relatively to the sleeve that the tumbler disk notches will assume positions about midway between the sleeve 30 grooves, leaving unrecessed peripheral portions of the disk in bridging relations to the sleeve grooves. The sleeve E is made with spur gear teeth *s*. J represents an arm pinned or keyed rigidly to the starting shaft B next to the rear of the sleeve E, and it carries at its outer end portion axle-united 35 spur gear wheels M and N, the one M being of greater diameter than the one N, the axle *t* uniting these two gear wheels being rotatable in and through the arm J by which it is revolvably carried. Next to and rearward beyond the arm J is another sleeve Q having 40 spur gear teeth *u* formed as part thereof, which are in mesh with the gear wheel N; and the end face of this sleeve Q has ratchet teeth *v* as shown in Figs. 2 and 5 with which engage the pawls *v²* provided in the fixture 45 R, the dowel R² of which engaging through a stationary part S preventing rotation of the fixture R, although the same is bodily movable forwardly and rearwardly as one with the device when thrown out of or into 50 clutch with the engine shaft.

T represents a shell or casing which encloses the sleeve Q, arm J and the gearing.

In the engine starting or cranking up action, the rotation of the crank, through the 55 pawls in engagement in the grooves in the flange like portion D of the starting shaft, causes the rotation of such shaft in exactly the same manner as if the crank were permanently affixed to the shaft and at such 60 time the peripherally notched and gear toothed sleeve, E, and the tumbler disk G, are also revolved, causing the revolution in a circular path of the axle united pinions and a rotative movement of the sleeve which 65 has the ratchet teeth in its end face and

which is caused to click past the pawls *v²*; but these planetary and rotative movement of the parts just referred to are merely incidental to the character of the mechanism and do not in any way contribute to the engine starting operation. But in case of a 70 back fire in which the starting shaft rotates counter clockwise, the revoluble arm T will carry the axle united spur gears in the reversed direction, and no rotation can be now 75 imparted to the gear-toothed sleeve Q because the latter is restrained from reversely moving by the pawls *v²*.

The gear N in circularly revolving around and in mesh with the gear teeth of the pawl restrained sleeve will derive a comparatively rapid rotation, and with it a rotation of the axle or uniting shaft *t*, and the other somewhat larger spur gear wheel M connected thereto; and this latter gear wheel which is 80 of less diameter than the toothed sleeve E will cause a rotation of the last named sleeve in the opposite direction from that of the reversed rotation of the starting shaft so that the alined grooves or notches in the 85 sleeve E and in the shaft flange D will be thrown out of alinement, with the effect,— by reason of the V-shape, for cam action, of the walls of the grooves, of outwardly forcing the pawls *k* carried in the crank hub 90 and placing them disengaged from the said parts D and E as well also as from the notches in the tumbler disk G. And so soon as the tumbler disk becomes disengaged by the pawls, it is free to have its slight degree 95 of rotative movement relatively to the grooved sleeve E under the torsional action of the spring *r*, whereby the notches in its edge will all be carried out of registry or alinement with the notches in the sleeve; 100 and thus even although in the continued reversed running of the starting shaft and the mechanism actuated thereby, the grooves *g* and *h* may periodically aline with each other, the pawls, nevertheless, will be restrained from reentering such grooves and reestablishing, for uncomfortable or dangerous results, the connection between the 105 backwardly running starting shaft and the crank. After a back fire and the stopping 110 of the engine, the normal conditions and relations of the parts, as shown in Fig. 2, for cranking up, will be reestablished merely by turning the crank in the forward direction. 115

The fact that the circular tumbler disk having the peripheral notches therein is diametrically slightly greater than the diameter of the peripherally grooved sleeve, insures in the forward rotation of the hub 125 of the crank, the entrance of the ends of the pawls into the mouths of the notches in the tumbler disk, effecting engagements between the pawls and such disk sufficient to cause the rotative movement of the latter 130

around on the end of the grooved sleeve to the extent limited by the pins *p* engaging in the slots in the disk,—and against the rotation of the torsion spring, and so that 5 the tumbler disk notches aline or register with those of the sleeve; and a greater or less extent of rotative movement of the crank hub, the pawls of which are partially sunk within the notches in the edge of the 10 tumbler disk, will rotatively force the latter and the sleeve which is pin and slot engaged therewith both around together so that very shortly the grooves of the tumbler disk and sleeve will be brought into longitudinal alinement with the grooves in the 15 flange on the end of the shaft, whereupon the pawls will be spring pressed not only into the bottoms of the tumbler disk grooves but also to bottoming engagements in the 20 grooves of the sleeve and said shaft flange, thus again connecting the crank with the starting shaft.

I claim:—

1. In a safety starting device for explosive engines, in combination the starting shaft having as a part thereof a cylindrical portion which is provided with a plurality of peripheral grooves, a gear-tooth-provided sleeve surrounding the shaft adjacent 25 said cylindrical peripherally grooved portion of the latter and having a series of peripheral grooves in arrangement corresponding to and adapted to aline with those of such cylindrical portion, another sleeve 30 loosely encircling the shaft having gear teeth and having ratchet teeth, and a fixture provided with a pawl for engagement in the latter teeth, an arm unitary and revoluble with the shaft and carrying axle-united gear wheels which are in mesh with the gear teeth of both said sleeves, and a starting 35 crank having a pawl adapted for engagement in the alined grooves of the first named sleeve and of the said cylindrical 40 shaft portion.

2. In a safety starting device for explosive engines, in combination the starting shaft having a cylindrical portion which is provided with a plurality of peripheral 45 grooves, a gear-tooth-provided sleeve surrounding the shaft adjacent said cylindrical peripherally grooved portion of the latter and having a series of peripheral grooves in arrangement corresponding to 50 and adapted to aline with those of such cylindrical portion, a circular centrally apertured disk of slightly greater diameter than the said sleeve and cylindrical shaft portion, and having peripheral grooves in 55 arrangement corresponding to those in such parts, having its location between such parts, having a lost motion engagement with the end of the sleeve and having a spring for rotatively moving it relatively 60 to the aforesigned sleeve, another sleeve 65

loosely encircling the shaft having gear teeth and having ratchet teeth, and a fixture provided with a pawl for engagement in the latter teeth, an arm unitary and revoluble with the shaft and carrying axle-united gear 70 wheels which are in mesh with the gear teeth of both said sleeves, and a starting crank having a pawl adapted for engagement in the alined grooves of the first named sleeve and of the said cylindrical 75 shaft portion.

3. In a safety starting device for explosive engines, the combination with the starting shaft having a cylindrical flange-like portion having a series of grooves therein, and a sleeve loose on the shaft adjacent said groove provided shaft flange and having a corresponding series of peripheral grooves adapted to aline with those of said flange, the crank having a hub surrounding said 80 grooved shaft flange and sleeve, and having a pawl adapted to engage in alined grooves of said parts, and means operable by a reversed rotation of the starting shaft to cause a rotative movement of the sleeve relatively to 85 the grooved shaft flange to force the pawl out of engagement with both of said grooved parts.

4. In a safety starting device for explosive engines, the combination with the starting shaft having a cylindrical flange-like portion having a series of grooves therein, and a sleeve loose on the shaft adjacent said groove provided shaft flange, and having a corresponding series of peripheral grooves 90 adapted to aline with those of said flange, the crank having a hub surrounding said grooved shaft flange and sleeve, and having a pawl adapted to engage in alined grooves of said parts, a disk surrounding the shaft, 95 between the end of the sleeve and the flange, of greater diameter than said parts, edge-wise grooved corresponding to the aforesaid sets of grooves, having a lost motion engagement with the sleeve, and having a spring operative thereon to rotatively move it relatively to the sleeve, and means operable by a reversed rotation of the starting shaft to cause a rotative movement of the sleeve relatively to the grooved shaft 100 flange to force the pawl out of engagement with both of said grooved parts.

5. In a starting device for explosive engines, in combination, the starting shaft having a flange thereon provided with a series of peripheral grooves, a sleeve loose about the shaft having a like series of peripheral grooves, the crank having a hollow hub loosely encircling the shaft flange and sleeve and having a pawl for engagement in 110 alined grooves of the shaft flange and sleeve, and differential gearing actuated by the shaft on its reversed rotation to move the groove sleeve rotatively relatively to the 115 shaft flange.

6. In a starting device for explosive engines, in combination, the starting shaft, having a flange thereon provided with a series of peripheral grooves, a sleeve loose about the shaft having a like series of peripheral grooves, a tumbler-disk loose about the shaft, having a pin and slot engagement with the sleeve, of slightly greater diameter than the sleeve and shaft flange, and having peripheral notches corresponding to those of the flange and sleeve, the crank having a hollow hub loose about the shaft and having a pawl for engagement in alined grooves of both the shaft flange and sleeve, and differential gearing actuated by the shaft on its reversed rotation to rotatively move the grooved sleeve relatively to the shaft flange.
7. In an explosive engine starting device, in combination, the starting shaft, having a flange like part provided with a series of peripheral grooves, a sleeve loosely encircling the shaft and having a like series of peripheral grooves, and also having gear teeth, a crank having a hollow hub loosely encircling the shaft flange and sleeve and having pawls for engagement in alined grooves of said shaft flange and sleeve, another sleeve loosely surrounding the shaft and having means for restraining it against reversed rotation, and said second sleeve being provided with gear teeth, and an arm revolvably carried by the shaft and having axle united gear wheels in mesh with the gear teeth on the two sleeves.
8. In an explosive engine starting device, in combination, the starting shaft, having a flange like part provided with a series of peripheral grooves, a sleeve loosely encircling the shaft and having a like series of peripheral grooves, and also having gear teeth, a crank having a hollow hub loosely encircling the shaft flange and sleeve and having pawls for engagement in alined grooves of said shaft flange and sleeve, another sleeve loosely surrounding the shaft and having means for restraining it against reversed rotation, and said second sleeve be-
- ing provided with gear teeth, an arm revolvably carried by the shaft and having axle united gear wheels in mesh with the gear teeth and having ratchet teeth, and a fixture closing the second sleeve, the arm, the axle united gears, and the gear toothed portion of the first named sleeve.
9. In a device of the character described, in combination, the starting shaft, having a circular flanged end portion provided with peripheral longitudinal grooves leading to one end of the flange, a sleeve of the same diameter as the flange, slightly separated therefrom and having a like series of peripheral grooves at its end toward the flange and provided at its opposite end with spur gear teeth, a centrally apertured tumbler disk encircling the shaft between the sleeve and shaft flange of slightly greater diameter than that of said sleeve and shaft flange having a pin and slot engaging with the sleeve and having a spring reactive between the sleeve and disk for rotatively moving the disk relatively to the sleeve, and provided with a series of peripheral notches corresponding in spacing to those of the sleeve and flange, an arm revolvably carried by the shaft at the rear of the sleeve, a second sleeve loosely encircling the shaft to the rear of the arm having spur gear teeth thereon and having ratchet teeth in its rear end, a fixture provided with a series of spring pressed pawls engaging said ratchet teeth, a pair of axle united gear wheels in mesh with the gear teeth of both said sleeves, and the crank having a tubular hub loosely encircling portions of the shaft flange the first named sleeve and the interposed disk, and provided with pawls for engaging in alined grooves in said shaft flange and first named sleeve.

Signed by me at Holyoke, Mass., in presence of two subscribing witnesses.

JOHN O. STANLEY.
